UNITED STATES PATENT OFFICE.

JAMES F. MCELROY, OF ALBANY, NEW YORK.

DESIGN FOR A CASING FOR ELECTRIC RADIATORS.

SPECIFICATION forming part of Design No. 25,593, dated June 2, 1896.

Application filed April 16, 1896. Serial No. 587,865. Term of patent 14 years.

To all whom it may concern:

Be it known that I, JAMES F. MCELROY, a citizen of the United States, residing in the city and county of Albany, State of New York, have invented and produced a new and original Design for a Casing for Electric Radiators, of which the following is a description, reference being had to the accompanying drawing, forming a part thereof.

10 The figure is a perspective view of my casing for electric radiators and fully illustrates my design.

The leading feature of my design consists in a casing for an electric radiator, of the 15 shape shown, provided with a series of openings A, separated by narrow bars B, placed near the upper front thereof, immediately below which is a plain solid surface C. Beneath said solid surface I arrange a series of 20 openings D, separated by narrow bars E, said

bars retreating from the lower edge of said plain solid surface downward, forming a convex-concavo lower portion for the casing, connected at their lower ends with a rib or projection F, extending across the casing. 25 On the top of the casing I arrange the brackets G G, usually near each end, provided with bolt-holes.

My casing is constructed in such a manner as to present the same appearance from 30 each side.

What I claim as my invention, and desire to secure by Letters Patent, is—

The design for a casing for an electric radiator, as herein shown and described.

JAMES F. MCELROY.
